DESIGN FOR A GLOVE

Charles R. Kovar, Richmond Hill, N. Y., assignor
to Julius Kayser & Co., New York, N. Y., a cor-
poration of New York

Application June 27, 1936, Serial No. 63,533

Term of patent 3½ years

To all whom it may concern:

Be it known that I, Charles R. Kovar, a citizen
of the United States, residing at 102-32 Park Lane
South, Richmond Hill, Long Island, in the city
of New York, county of Queens, and State of
New York, have invented a new, original, and
ornamental Design for a Glove, of which the
following is a specification, reference being had
to the accompanying drawing, forming part
thereof.

Figures 1 and 2 are respectively a front view
and a back view of a glove embodying my new
design.

The entire glove is of ribbed fabric, the tex-
ture of which is shown in the drawing. The cuff
portion flares outwardly from the wrist where the
material is gathered to give the appearance of a
cord, and a plurality of longitudinally extending
ribs converge at the wrist and flare outwardly
in the cuff portion, as shown in Figure 2 of the
drawing.

I claim:

The ornamental design for a glove, as shown
and described.

CHARLES R. KOVAR.
